UNITED STATES PATENT OFFICE.

OSCAR GRAEVE, OF NEW YORK, N. Y., ASSIGNOR TO HARPER'S BAZAR, OF NEW YORK, N. Y.

DESIGN FOR A CAP PIECE FOR A MIRROR OR SIMILAR ARTICLE.

Application filed March 26, 1925. Serial No. 12,895. Term of patent 7 years.

To all whom it may concern:

Be it known that I, OSCAR GRAEVE, a citizen of the United States of America, residing at New York, in the county of New York and State of New York, have invented a new, original, and ornamental Design for Cap Piece for a Mirror or Similar Article, of which the following is a specification, reference being had to the accompanying drawing, forming a part thereof.

In the drawing,

The figure is a front view of a cap piece for a mirror or similar article, showing my new design.

I claim:

The ornamental design for a cap piece for a mirror or similar article, as shown.

OSCAR GRAEVE.
